SECTIONAL PARABOLIC ANTENNA SYSTEM

De Witt Rugg Goddard, Riverhead, N. Y., assignor
to Radio Corporation of America, a corpora-
tion of Delaware

Application June 24, 1943, Serial No. 492,032

9 Claims. (Cl. 250—11)

1

This invention relates to a new and useful split parabolic antenna system for use with an ultra high frequency radio transceiver.

An object of this invention is to provide an efficient light weight compact portable parabolic antenna for use in ultra high frequency systems for two-way voice communication. My invention is particularly useful for short waves of the order of ten centimeters in length.

Another object of this invention is to provide a portable waterproof three-piece parabolic antenna in which each separate portion is insulated from the other.

My invention employs a novel construction wherein a parabolic reflector is split into three pieces, namely, a center section and two side sections. Suitable means for removably fastening the sides on the center section are provided.

A feature of this invention resides in the fact that the center section of the parabolic reflector serves to form a portion of a control box which houses the radio frequency unit and is arranged with another box or cover portion to house the side sections and other devices.

Parabolic reflectors are old in the art, there being many different arrangements. Generally, they are large in size, and therefore cumbersome and heavy to carry. This invention overcomes these objections since by splitting the reflector into three major component parts, capable of being readily assembled, detached and stored away in a suitable container, portability, without loss of electrical efficiency, as will be explained later, is insured.

The parabolic reflector of this invention is particularly adapted for forming the antenna system of a portable two-way voice radio communication system operating at a wavelength of about ten centimeters, although, obviously, the invention is not limited to operation at this frequency. The antenna system described herein is intended to be used with a transceiver similar to the one described in a copending application of K. MacLean and DeWitt R. Goddard, filed May 20, 1943, Serial No. 487,722.

This invention will best be understood by referring to the accompanying drawings in which:

Fig. 1 is a front elevation of the split parabolic reflector of this invention.

Fig. 2 is a cross-section taken on 2—2 of Fig. 1.

Fig. 3 is a perspective view partly in section showing a portion of one of the side sections.

Fig. 4 is a perspective view of the box portion formed by the center section of the parabolic reflector, and

Fig. 5 is an end view of Fig. 4.

2

Referring now in detail to Figs. 1, 2 and 3 of the drawings, the center section 1 is shown mounted upon a telescoping tripod 2. On each side of the center section there are located side sections or wings 3 and 4 which are arranged to be detached from the center section 1 by means of a flat arcuate clamp strip 5. The end portions of the side sections are riveted to an angular member 6 which is arranged to slide under the arcuate strip 5. The side sections 3 and 4 are attached and detached by a thumb screw 7 which engages the slots 8 in the angular portion 6 and passes through the arcuate strip 5. The angular member 6 is provided with a plurality of slots 8 which are shown more in detail in Fig. 3 of the drawings. It will be seen that the thin parabolic reflecting surface 3 has the special aluminum angular portion 6 riveted thereon by means of rivets 6A. This angle material contains a circular perforation 5A located at the top and several half round notches 8 which are distributed along its edge. The main center section or box portion 1 contains an arcuate strip 5 which is held in position by means of three loose fitting rivets 6B and the knurled thumb screw 7 clamps the side sections 3 and 4 together. At the upper left hand corner of the box portion a stud 5B protrudes about one quarter of an inch beyond the surface of the strip 5. The threaded brass plate 7A is arranged to receive the threaded thumb screw 7. The plate 7A is fastened to the sides of the wood box 1 by means of small screws 7B. The center section or box portion 1 is provided with a metallic connection bushing 9 which is arranged to receive a detachable antenna radiator member 10. Radiator 10 is in the form of a simple dipole located at the end of a coaxial transmission line (not shown) and isolated therefrom by two quarter-wave sections. In front of the dipole 10A and insulated therefrom, is another dipole 10B which is used as a reflector. The latter is insulated from 10A since it is molded in thermoplastic insulating material such as lucite or polystyrene. The arrangement as a whole is such as to throw the majority of the radiations against the parabolic reflecting surfaces 1, 3 and 4 of the reflector. The lower portion of the center section has located therein a threaded flange member 11 which is threaded at 12 to receive a clamping bolt 13 for securing the center section to the tripod 2. To the right of flange 11 there is located a connection socket 14 which is arranged to receive a plug and cable 15 which connects the radiator 10 and transceiver to the battery and vibrator power supply box 16 located at the base of the tripod. Connection is made from radiator 10 and

transceiver to the socket 14 by means of leads 17 which are housed in the rear portion within the box transceiver portion of the center section.

As the parabolic antenna reflector unit of this invention is intended for outdoor use, I prefer to cover the entire surface of the antenna radiator 10 and the members 1, 3 and 4 with a low loss insulating material such as Amphenol to avoid detuning effects due to rain, snow or ice forming on the antenna itself. A coaxial line is preferred to feed the antenna which is isolated by two quarter wavelengths arranged in the usual fashion.

Referring to Figs. 4 and 5 of the drawings, there is shown how the cover and box portions of the center section are joined for carrying. The cover portion 20 serves for enclosing the side sections and also other control devices such as the radiator 10, head-phones 13, and plug and cable 15, which devices are located within the confines of the box cover portion when the box is closed. The cover portion 20 is provided with a carrying handle 21 and is secured to the box or transceiver portion of the center section by means of suitcase clasp members 22 and 23.

The lower portion of center section 1 contains a radio frequency device in the form of a transceiver which occupies approximately the lower third portion of the box. Its tuning and volume control knobs 24 are located on a panel at the rear of the box. Access to these controls is accomplished by having an aluminum cover plate 25 pivotally secured to the box by means of a hinge 26. Fastened to this cover plate are two inwardly folding canvas shields 27 which are arranged so that in the operation of the transceiver the plate 25 and canvas shields 27 in the open position constitute an effective rain shield. In Fig. 2 the cover plate and shield are shown in the closed position with the open position shown by dash lines. In Fig. 4 the rain shield is indicated in the open position with the control knobs 24 exposed for operation. To transport the reflector the canvas shields are folded inwardly, then pressed down and covered by the aluminum plate 25. At the lower portion of plate 25 there are two leather straps 28 which are snapped by means of glove fasteners 29 to the bottom of the box 1, as shown in Fig. 5.

In the operation and assembly of this system the perforation 5A of the wing or end sections is placed over the stud 5B and then the wing is swung into operating position so that the angle portion of the wing slides beneath the arcuate strip 5 until the notches 3 coincide with the rivets 6B and the thumb screw 7. The thumb screw 7 is then tightened and the wing slid into the position shown in Figs. 1 and 2 and the entire reflector is then complete. The antenna radiator 10 is plugged in the metallic connection bushing 9. The thumb screw 13 is tightened to secure the center section 1 to tripod 2. Electrical connection from the transceiver to the power supply 16 is made by means of cable and plug being inserted in socket 14. The parabolic antenna system is then ready for use.

It will be noted that no electrical contact is made between the side sections 3 and 4 and the center section 1. In fact I prefer to deliberately insulate the entire surface of the side sections with low loss insulating material for the reason that I find that poor contact generally causes noise in the receiver when electrical contact is made. It is to be understood that the parabolic reflector surface may be cut into other shapes than those shown in Figs. 1 and 2 and different

arrangements may be made where necessary to provide electrical contact between sections.

While I have indicated and described a preferred system for carrying my invention into effect, many modifications may be made without departing from the scope of my invention.

What I claim is:

1. A parabolic ultra high frequency antenna system comprising a rectilinear box portion having one of its surfaces forming a center section, and two side sections insulatingly secured to said box portion so as to be detached from each side of said center section.

2. A high frequency reflector comprising a central section, a pair of side sections removably secured thereto, the entire surface of said central section and said side sections being covered with a low loss insulating material to avoid detuning effects due to foreign material coming in contact with said reflector.

3. An ultra high frequency antenna system comprising a parabolic reflector including a rectilinear box portion having one of its surfaces forming a center section and having two side sections insulatingly secured thereto so as to be detached from each side of said center section, said box portion being adapted for enclosing a radio frequency device, a removable cover portion cooperating with said box portion for enclosing said side sections.

4. An ultra high frequency antenna system comprising a parabolic reflector including a rectilinear box portion having one of its surfaces forming a center section and having two side sections secured thereto so as to be detached from each side of said center section, said center section being arranged with straight ends to form a portion of a box for enclosing a radio frequency device, the entire surface of said center section and said side sections being covered with a low loss insulating material to avoid detuning effects due to foreign material coming in contact with said reflector, a cover portion cooperating with said center section for enclosing said side sections, and fastening means secured to the lower portion of an end of said center section for fastening the reflector to a tripod.

5. An ultra high frequency antenna system comprising a parabolic reflector including a rectilinear box portion having one of its surfaces forming a center section and having two side sections secured thereto so as to be detached from each side of said center section, the entire surface of said center section and said side sections being covered with a low loss insulating material to avoid detuning effects due to foreign material coming in contact with said reflector, said center section being arranged with straight ends in the form of a box, a cover portion cooperating with said center section for enclosing said side sections, a radio frequency device located in said center section, fastening means secured to the lower portion of an end of said center section for fastening the reflector to a tripod which is arranged at one end of said center section, and a socket portion located adjacent said fastening means for the tripod for electrically connecting said radio frequency device to a source of power.

6. A parabolic ultra high frequency antenna system comprising a rectilinear box portion having one of its surfaces forming a center section, two side sections secured to said box portion so as to be detached from each side of said center section, the entire surface of said center section

and said side sections being covered with a low loss insulating material to avoid detuning effects due to foreign material coming in contact with said reflector, an antenna radiator and a radio frequency device located in the central portion of said center section.

7. A parabolic ultra high frequency antenna system comprising a rectilinear box portion having one of its surfaces forming a center section, two side sections with angular slotted portions arranged to be detached from each side of said box portion, the entire surface of said center section and said side sections being covered with a low loss insulating material to avoid detuning effects due to foreign material coming in contact with said reflector, and mechanical engaging means secured to said box portion of the center section for the engaging angular slotted portions located at the ends of said side sections for fastening them to the center section.

8. An ultra high frequency antenna system comprising a parabolic reflector including a center section having two side sections secured thereto, the entire surface of said center section and said side sections being covered with a low loss insulating material to avoid detuning effects due to foreign material coming in contact with said reflector, said center section being arranged in the form of a rectilinear box, a transceiver lo-

cated within the box portion of said center section, a cover portion cooperating with said center section for enclosing said side sections when it is desired to transport said antenna system, fastening means secured to the lower portion of said center section for fastening the reflector to a tripod which is arranged at one end of said center section and a socket portion located adjacent thereto for electrically connecting said transceiver to a source of power.

9. An ultra high frequency antenna system comprising a parabolic reflector including a center section having two side sections secured thereto, said center section being arranged in the form of a rectilinear box, a radio frequency device located in the lower portion of said center section, an operating panel maintained at the rear of said center section, a hinged waterproof cover arranged to be folded over said panel, a cover portion cooperating with said center section for enclosing said side sections when it is desired to transport said antenna system, fastening means secured to the lower portion of said center section for fastening the reflector to a tripod which is arranged at one end of said center section and a socket portion located adjacent thereto for electrically connecting said radio frequency device to a source of power.

DE WITT RUGG GODDARD.
